CONTAINER POURING SPOUT

John M. Hothersall, Brooklyn, N. Y., assignor to
 American Can Company, New York, N. Y., a
 corporation of New Jersey

Application September 8, 1933, Serial No. 688,677

8 Claims. (Cl. 221—27)

The present invention relates to container dispensing and has particular reference to sealed containers or cans provided with pouring spouts effective for use by a sliding of the spouts into projecting pouring position and which after dispensing of a part of the can contents from the opened can may be returned to non-projecting position and form a temporary closure.

An important object of the invention is the provision of a closed can having a depression or seat formed in its wall for slidably retaining a pouring spout which is movable into pouring position by partial withdrawal from its seat and which assists in the proper discharge of the contents of the opened can when so withdrawn, and which also closes the opened can after it has been slid back into confined position within its seat.

A further object of the invention is the provision of a curved pouring spout having sliding engagement within a curved depression formed in the can, the curvature permitting raising of the spout over the rim of the can, with the spout end projecting in pouring position beyond the rim, this raising action being effected by withdrawal of the spout, at the same time sliding it within its seat.

The invention also contemplates the provision of a slidably curved reenforced pouring spout confined, in one position, within the can wall, the latter being initially closed to seal its contents during shipment, the can being opened by a piercing of its wall at a point in alignment with a discharge opening in the spout when the latter is positioned for pouring, following which the spout may be slid back into confined and protected position within the can walls, and in the latter position it acts as a temporary reclosure.

Numerous other objects and advantages of the invention will be apparent as it is better understood from the following description, which, taken in connection with the accompanying drawing, discloses a preferred embodiment thereof.

Referring to the drawing:

Figure 1 is a perspective view partially broken away of a can embodying the present invention;

Fig. 2 is a plan view of a part of the container illustrated in Fig. 1; and

Figs. 3 and 4 are enlarged sectional views taken substantially along the line 3—3 in Fig. 2, the former view illustrating a pouring spout fully seated within the sealed can wall prior to opening of the can, and Fig. 4 illustrating the opened can with pouring spout withdrawn into pouring position.

An embodiment of the invention as exemplified

in the drawing comprises a can body 11 having a bottom 12 and a top 13 secured to the body in any suitable manner as by the usual double seam. The top horizontal wall of the end 13 (designated by the numeral 14) is spaced a short distance below the seamed edge 15 which provides a surrounding rim for the top of the can.

A depression 21 is formed in the wall 14 and is outlined by spaced horizontal walls 22, an end wall 23 and a connecting curved bottom wall 24. The curvature of the wall 24 and its location within the top of the can is such as to merge this curved wall directly into the horizontal wall 14 at the left end (Figs. 3 and 4) of the depression, this being opposite to the end wall 23.

The wall 24 is preferably weakened in two places by score lines or otherwise, a scored star 25 (Fig. 2) and a similar star 26 (Fig. 1) being illustrated for this purpose. The curved can wall 24 is adapted to be punctured at these places in any suitable manner as by a pressing in of the metal at the scored star 25 to provide a dispensing opening and at the star 26 to provide a vent opening. Any suitable puncturing tool may be used for the breaking of the wall at the two points and this action constitutes an opening of the can, as will be hereinafter more fully described. Until the can is thus opened for pouring the top is entirely closed in an hermetic manner.

A pouring spout 31 is provided and is preferably formed with a curved wall 32 shaped to correspond with the curved can wall 24 and the spout wall has side reenforcing curls 33 which extend nearly its full length. These curled sides hold the wall 32 in its curved shape.

The spout 31 is adapted for sliding movement within the depression 21 and to permit easy manipulation one end is curled over into a finger hold 34. The spout has a longitudinal movement within the depression and is retained in sliding position by a strap 35 which is formed with side wings 36, the latter connecting with the center of the strap in curved holding seats 37.

Strap 35 is mounted on the can wall 14 and its side wings 36 are secured to the wall on opposite sides of the depression 21 in any suitable manner, as by welding. The center part of the strap extends across the depression and its formed seats 37 slidably engage the reenforcing curls 33 of the pouring spout 31, this construction making a better sliding connection for the spout.

When the filled can is sealed and shipped the pouring spout 31 is fully disposed within the depression 21, as illustrated in Fig. 3, its finger hold end 34 abutting against the end wall 23

of the depression seat. In such position the opposite end of the pouring spout is below the can top wall 14, all of the spout being thus fully positioned below the surrounding rim 15 and out of the way. This permits stacking of one can on another.

When the can is to be opened the spout 31 is first partially withdrawn or pushed out of its seat (Fig. 4) the finger hold 34 providing easy manipulation for this purpose. By reason of the curvature of the can wall 24 and the spout wall 31, as previously set forth, the end of the spout is elevated above when pulled out and projects a substantial distance beyond the can. The finger hold 34 strikes against the back edge of the strap 35 and this provides a stop for definitely locating the spout in its pouring position.

The strap 35 is provided with an aperture 36 and the spout wall 31 is similarly apertured at 38, 20 the two openings 38, 39 when the spout is in pouring position, being in alignment with one another and in alignment and directly above the scored star 25 formed in the curved wall 24 of the spout seat. The can is opened by inserting 25 any suitable pointed instrument through the apertures 38, 39 and puncturing the can wall forcing down the metal at the scored star 25 and forming a perforation 41 (Fig. 4). A second perforation 42 is also preferably made in the can 30 wall by forcing down the metal adjacent the star 26, this part of the wall being free of the spout at such time.

With the can opened in this manner and the pouring spout in extended position, dispensing of the can contents is had by suitably holding and tipping the can so that its contents flows out through the perforation 41, apertures 38, 39 and thence along the top surface of the strap 35 (between the formed walls 31) and thence over the 40 top surface of the wall 32 of the spout between its side curls 33 and out over its end, the point of discharge being at a distance beyond the rim 15 of the can.

With many products for which such a can is used only small quantities will be withdrawn at a time and after each pouring action the can is again returned to its upright position (Fig. 4). Where the contents is a liquid, such as cooking oil, there will be some clingage to the spout and strap parts. After the can has been returned to upright position this liquid will drain back and most of it passes back through the openings 38, 39, 41. Some of the drainage, however, particularly below or back of the strap aperture 38, flows down along the upper surface of the strap.

The wall 32 of the pouring spout 31 is formed with a drainage hole 45 (Figs. 1 and 4) which is preferably cut through the wall at the base 60 of the curled finger hold 34 and the liquid flowing over the back of the strap passes through this drainage opening. Flowing down along the upper surface of the depression wall 24 it passes back into the can by way of the vent aperture 65 42. When the slide spout 31 is pushed back into its seated position within the depression 21 any adhering liquid will be carried back and into the vent opening 42.

Where a rectangular can body 11 is desired, this being a popular style of can for vegetable cooking oil or compound, the pouring spout depression 21 is preferably formed along a diagonal line, which passes through one corner of the can, this being illustrated in the present embodiment 70 of the invention. Such an arrangement permits

positioning of the extended end of the pouring spout out and over the corner of the can and in many ways is more desirable as a pouring position than it would be along the straight side of the can. It is of course immaterial as far as the present invention is concerned where the spout is located relative to the can, the best pouring position being desirable.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. A container having a rim and comprising a wall having a curved depression directed upward at its outer end, the portion of the wall within the depression being closed and adapted to be perforated to open the container, and a curved pouring spout slidably engaged within said depression and movable along said depression and over said rim and into a pouring position, said spout having an aperture which is adapted for alignment with the perforation formed in the opened container for dispensing of the container's contents by way of the spout.

2. A container comprising a wall having a curved depression surrounded by a projecting rim, the portion of the wall within the depression having a weakened closed portion adapted to be perforated to open the container, and a curved pouring spout slidably engaged within said depression and movable into pouring position with its outer end extending beyond and over said rim, said spout having an aperture which is adapted for alignment with the perforation formed in the opened container for dispensing the container contents by way of the spout and over said rim.

3. A container comprising a wall having a depression formed therein which is set off by side walls and a connecting curved wall, the depression being surrounded by a projecting rim, and a pouring spout having a curved wall adapted for sliding engagement with the connecting curved wall of said depression, the curvature of said depression wall and said container wall being such as to permit the raising of one end of the spout over said projecting rim when the spout is slid into its pouring position and said depression also provides substantial confinement of the said spout when it is moved into non-pouring position, both container and spout having discharge openings after the container is opened which are brought into alignment by movement of the spout into pouring position.

4. A container comprising a rectangular body, bottom and top ends secured to said body and sealing said container, said top end having a curved depression formed along a diagonal line projecting through one corner of said body and provided with side and bottom walls, the latter being closed and weakened and adapted to be perforated to open the container, and a curved pouring spout having sliding movement within said depression and into a pouring position with one end projecting beyond the adjacent corner of the said body, the said spout having an aperture adapted for registration in its discharge position with the perforation in the bottom wall of said opened container to provide for dispensing

of the container contents through said spout.

5. A container comprising a body, bottom and top ends secured to said body and sealing said container, said top end having a depression formed with side and end walls and a curved bottom wall, the latter being closed and adapted to be perforated to open the container, and a sliding pouring spout fitting within said depression and having a bottom apertured wall 10 shaped to fit the curve of said curved depression wall and having a finger hold by means of which the spout is moved into a pouring position with one end projecting beyond said container body and with its aperture in alignment with the perforation made in the container, said finger hold also providing means by which the spout is moved into a non-pouring position against the end wall of said depression.

6. A container comprising a wall having a depression, a portion of the wall within the depression being closed and weakened and adapted to be perforated to form a dispensing opening and a vent opening, a pouring spout located in said depression and having an aperture for pouring 25 and a vent aperture, and a retaining strap secured to said container wall and extending over said depression for slidably holding said pouring spout therein, said strap having an opening for its movement relative to said container, and reinforcing side members formed along the edges of said curved wall for retaining the curved shape of the spout wall and for maintaining its sliding fit with the container wall, said drain- 30 age aperture permitting the draining back, into the container, of liquid clinging to the spout after it has been used for pouring.

7. A container comprising a wall having a depression, a scored portion of the wall within the depression being weakened and adapted to be perforated to form a dispensing opening, a pouring spout located in said depression and having an aperture extending through a wall thereof and also having curled reinforcing side walls on opposite sides of said aperture, and a retaining strap secured to said container wall and having formed portions to slidably fit the side walls of 10 said spout and having an aperture between said formed portions, said strap extending over said depression and slidably holding said pouring spout therein, the latter being movable into a pouring position with its said aperture in alignment between said container dispensing opening and the aperture in said strap.

8. A pouring spout for a liquid container comprising a curved spout adapted for sliding engagement within a depression formed in the wall 20 of the container, said curved spout having discharge and drain apertures, the former being adapted for registration with a discharge opening formed in the container wall, a finger hold formed at one end of said spout and providing 25 for its movement relative to said container, and reinforcing side members formed along the edges of said curved wall for retaining the curved shape of the spout wall and for maintaining its sliding fit with the container wall, said drain- 30 age aperture permitting the draining back, into the container, of liquid clinging to the spout after it has been used for pouring.
